DESIGN FOR A DRAWER PULL

Donald A. Morand, Portland, Oreg.

Application July 6, 1936, Serial No. 63,660

Term of patent 7 years

To all whom it may concern:

Be it known that I, Donald A. Morand, a citizen of the United States and a resident of Portland, in the county of Multnomah, State of Oregon, have invented a new, original, and ornamental Design for Drawer Pull, of which the following is a specification, reference being had to the accompanying drawing, forming a part thereof.

Figure 1 is a perspective view of a drawer pull showing my new design.

Figure 2 is a side elevation of the drawer pull.

Figure 3 is a sectional elevation on a larger scale taken on the line 3—3 of Figure 2.

I claim:

The ornamental design for a drawer pull as shown.

DONALD A. MORAND.
